TWO-SIDED DISPENSING PUMP

Filed July 17, 1928

UNITED STATES PATENT OFFICE

THOMAS B. BENNETT AND LE ROY A. PRESCOTT, OF MUSKEGON, MICHIGAN, ASSIGNEES
TO BENNETT PUMPS CORPORATION, OF MUSKEGON, MICHIGAN, A CORPORATION OF
MICHIGAN

TWO SIDED DISPENSING PUMP

Application filed July 17, 1928. Serial No. 293,381.

This invention relates to a dispensing pump particularly useful for dispensing liquids such as lubricating oil at service stations for motor vehicles.

5 We have devised and made application for patent on an enclosing housing or canopy for oil dispensing pumps to be used at service stations wherein the tanks containing the oil with the attached pumps may be out of doors in which case the motor vehicles to be serviced will come to either side of the battery of tanks. In such case it is desirable that the dispensing of oil may be had equally well at either side of the tank back.

10 15 In pursuance of this object we have provided a dispensing pump adapted to be attached to an oil containing tank in which delivery may be had at two opposed sides of the pumps or tanks and while delivery is being made at one side no oil will escape at the other side, means being provided to fully insure against undesirable escape and loss of oil.

An understanding of the invention for the 20 attainment of these ends, as well as many others not at this time specifically set forth, may be had from the following description taken in connection with the accompanying drawing in which,

25 30 The figure is a side elevation of a pump made in accordance with our invention, certain parts thereof being broken away and shown in section for a better disclosure of the interior construction.

35 40 45 50 The top 1 of a tank is shown to which the pump is designed for attachment extending above the same when in use. The pump structure includes a lower member 2 in the form of a hollow casting which has a downwardly extending and downwardly tapered lower portion 3 with an inlet opening at its bottom and with an inlet pipe 4, which extends into the tank, having a threaded connection at its upper end with said section 3 at the opening therein. This lower member of the pump extends partly into the tank through an opening made in the top 1 and is provided with an outwardly extending annular ring 5, as shown, through which bolts may be passed to permanently secure the

pump in place. A ball valve 6 normally closes the inlet opening to the pump at the lower end of the tapered section 3.

The upper end of the member 2 also is provided with an opening, around and extending above which is a pump cylinder 7 secured in any suitable manner to the upper end of the member 2. The cylinder 7 at its upper end has a head 8 joining with which is a lower end of a glass cylinder 9 of a smaller diameter than the cylinder 7. The upper end of the glass cylinder 9 carries the outlet nozzle member 10 of the pump which has an opening in its lower side to communicate with the upper end of the cylinder 9, and is formed with an annular flange 11 embracing the upper end of said cylinder 9, through which any desired number of tie rods 12 may pass to connect with the head 8 described and thus permanently bind the parts together.

The upper nozzle member 10 of the pump construction is hollow and includes two oppositely extending hollow arms 13 each terminating at its outer end in a nozzle member 14 which has a delivery outlet 15 at its lower end as shown at the right of the drawing.

The upper end of each nozzle 14 is internally bored and threaded to receive a closing cap 16. A valve rod 17 passes through the cap and at its lower end is equipped with a closing valve 18, which in lower position fills the outlet opening 15. A spring 19 around the rod 17 and between the valve and the nut 16 normally tends to move the valve to and hold it in closing position. At the upper end of the rod 17 a handle 20 is mounted for pivotal movement and has cam extensions 21 bearing against the upper side of the nut 16 whereby on turning the handle 20 to vertical position, rod 17 with its attached valve 18 is lifted and is retained in lifted position as shown at the right in the figure of the drawing; but by grasping the handle and turning the same to horizontal position as shown at the left the valve is released to take its lower outlet closing position.

A piston 22 is mounted within the cylin-

der 7 for vertical reciprocation. It has an opening or openings therein which are normally closed by ball valves 23 seating by gravity. A link 24 is pivotally connected at 5 its upper end to the piston and extends downwardly into the member 2 having pivotal connection at its lower end to a crank arm 25 fixed to a shaft 26 journaled in opposite sides of the member 2, and having an operating lever 27 secured to the same at one end outside of said hollow member 2. The shaft 26 may be rocked manually by grasping the lever 27 and turning it from the full line position to the dotted line position or vice 15 versa.

When the lever is in the full line position shown, it may be grasped and swung to the dotted line position whereupon the piston 22 is moved upwardly in the cylinder and 20 any oil above said piston is forced outwardly through an outlet opening 15 which has had its closing valve 18 lifted. On the upstroke of the piston the valve or valves 23 remain closed and oil is drawn past the valve 6 into 25 the lower hollow member 2 of the pump construction following the piston on its up movement. The length of the up stroke of the piston may be regulated by an adjustable screw 28 threaded through one side of the 30 member 2 and against which the arm 25 strikes when the piston has been lifted to its uppermost position. On swinging the lever 27 back, the piston is moved downwardly in the cylinder, valve 6 closes the inlet pipe 4 35, while the valve 23 permits the passage of liquid by the piston to above the same.

The operator stands on the far side of the lever 27, with reference to the pump proper, and grasps it with either his left or his right 40 hand according to the direction in which he is facing.

The upstroke of the piston raises the oil and expels it through the chosen nozzle as well as pulls new oil out of the storage reservoir, 45 whereas the downstroke merely forces the oil through the valve in the piston and hence more force is needed during the former stroke.

When the operator uses his right arm, 50 which is usually stronger than his left, to operate the lever, the power or more difficult stroke occurs when the lever is traveling away from him but when he uses his weaker arm he is able to avail himself of its full 55 force and expediently operate the pump as the more difficult stroke occurs when he is pulling the lever towards himself and such a demand is more easily met by pulling than by pushing. In other words his body 60 may be utilized more readily in pulling the lever than in pushing it.

There is provided in the structure described the capability of delivering oil at either side of the pump or tank. The point 65 of delivery is selected by raising the valve

18 in the nozzle at the selected side leaving the other valve in closed position. The pressure of spring 19 serves to securely hold a valve in its closed position but should there be any tendency to leak by the valve it is obviated by the increased pressure coming against the upper side of the valve from the oil forced upwardly on the up stroke of the piston.

The construction described is very durable, 75 practical and serviceable. A double outlet is provided in a single pump with insurance that delivery from one outlet only shall be had at a time and with an ability to have the delivery at the side of the tank where the motor vehicle has stopped for oil replenishment. This makes the construction very practical and satisfactory in all respects. The invention is defined in the appended claim and is to be considered comprehensive of all forms of 80 structure coming within its scope.

We claim:

A pump comprising a vertical cylinder having an inlet end and an outlet end, a chamber below the inlet end of the cylinder, a one way valve opening into the chamber, a piston in said cylinder, a one way valve leading upwardly through the piston, a lever located outside of said chamber and having a shaft extending into said chamber, a crank arm on said shaft, a link connecting the crank arm and the piston, said link and crank arm being about the same length whereby the said link is oscillated about its connection to the piston through an angle substantially equal to the degree of oscillation of the crank arm when the lever is actuated, said lever being accessible from opposite sides of the pump for manual operation, a conduit communicating with the outlet end of the cylinder and extending to opposite sides of the cylinder and having outlet openings at its respective opposite ends and manually and independently operable means for opening or closing each of said outlet openings.

In testimony whereof we affix our signatures.

THOMAS B. BENNETT.
LE ROY A. PRESCOTT.
